UNITED STATES PATENT OFFICE.

LEONARD E. ALLYN, OF WEST MYSTIC, CONNECTICUT.

PRESSURE PUMP.

Application filed February 9, 1923. Serial No. 618,034.

To all whom it may concern:

Be it known that I, LEONARD E. ALLYN, a citizen of the United States, residing at West Mystic, in the county of New London 5 and State of Connecticut, have invented certain new and useful Improvements in Pressure Pumps, of which the following is a specification.

This invention relates to improvements 10 in pressure pumps, one object of the invention being the provision of a wet and dry air pump for use with stationary or marine engines.

A further object of this invention is the 15 provision of a device of this character which will dispense with the large air pumps and therefore give more efficiency in the same working conditions by saving extra power, weight and space, that is now 20 necessary with the present type of air pumps.

A still further object of this invention is the provision of a novel arrangement of 25 pump in which the steam passing through certain nozzles creates sufficient velocity to produce a sucking action in a pipe, that is, connected to a condenser so that air and vapor is drawn through a space surrounding the nozzle and discharged through a 30 reduced portion adjacent the mouth of the nozzle into a discharge pipe, thus causing the steam passing through the nozzle to create a velocity to remove the condensate air and vapor from the condenser and maintain 35 a desired vacuum.

In the accompanying drawings:

Figure 1 is a side elevation partly in section of the main member of the present pump.

40 Figure 2 is a section on line 2-2 of Figure 1.

Referring to the drawings, the numeral 5 indicates the motive fluid admitting pipe which leads into the supply valve casing 45 6 which in turn is connected to the nozzle block chamber 7 carrying the nozzle block 8 at the outer end thereof. This nozzle block is threaded into the inlet end 9 of the main ejector housing 10 which is here shown 50 as provided with the chamber 11 having the reduced portion 12 and the enlarged flared portion 13 at its mouth. The nozzle block 8 is provided with a plurality of nozzle openings 14 and 15, the nozzle 14' being 55 removable and concentric and the other nozzles 15' being similar and disposed

thereabout, with the outlets directed angularly toward the center. The outlet end of the nozzle 14' projects beyond and through the threaded enlargement 17 which receives the exteriorly threaded boss 18 of the condensate ejector nozzle 19, into which the outlet end of the nozzle 14' projects, terminating at a point approximately above the center of the inlet 21 of the condensate 60 ejector, a pipe 22 being connected to the condensate suction pipe 23. Pipe 23 is the condensate suction pipe and is connected to bottom of condenser C.

An air and suction pipe 25 connected to 70 the condenser enters the chamber 11 at a point opposite to pipe 23 which makes pipe 23 a suction independent from suction pipe 25.

From the foregoing description, taken in 75 connection with the drawings, it is evident that when steam pressure is admitted through nozzle block 8 that a suction action is created both within and without the nozzle 19 and therefore a suction action is had to the pipe 22 and through the pipe 23, through which the condensate is properly elevated and discharges into the enlarged flared portion 13 into the main discharge 80 pipe 24 of the air and vapor remover 85 discharge.

Thus with this construction the apparatus 90 is partially working as an air remover when there is not sufficient condensate at the bottom of the condenser to be removed.

Steam passing through nozzle openings 95 15 creates sufficient velocity to create a suction action in pipe 25 which is connected to the condenser, not shown, and draws the air, vapor, etc., through 11 and discharges 100 through the reduced portion 12 into and through the enlarged flared portion 13 into the discharge pipes 24. By this means steam passing through nozzle openings 14 and 15 creates a velocity sufficient to remove 105 the condensate air and vapors from condenser and maintains a desired vacuum.

The present device could be constructed 110 in different sizes to meet requirements.

What is claimed as new is:

In a device of this character, the combination with a valve controlled motive pressure fluid supply, a valve chamber, an 115 ejector chamber having an outlet and two inlets, a suction pipe connected to one inlet, a condensate pipe projecting into the ejector 120 housing, a nozzle block at the junction be-

12
tween the nozzle chamber and the ejector chamber and provided with a concentric nozzle opening and a plurality of circumferential nozzle openings, the latter openings being in direct communication with the chamber of the ejector housing, a condensate nozzle provided with a main chamber in communication with the condensate pipe, and a propelling and suction nozzle in communication with the center nozzle 10 of the block.

In testimony whereof I affix my signature.

LEONARD E. ALLYN.
